Apollos Richmond's New Design for a Portable Grate. Patented Sept 11 1849.

Fig. 2.

Fig. 1.

Dec. 131

A. G. Barstow & Co. Ass^{es} of Apollos
Richmond, of Providence. R. I.
Letters Patent N° 231. dated September 11th 1847.

numnumnum
The Schedule referred to in these Letters Patent and making part
of the same
numnumnum

To all Persons to whom these Presents shall come

Be it Known - That I Apollos Richmond, of Providence, in
the County of Providence, and State of Rhode Island, have in-
vented or produced a new design for the front of a portable
grate, and I do hereby declare that the following is a full and

exact specification of the same reference being had to the accompanying drawings, which form a part of this specification.

Fig. 1. of said drawings is an elevation of my new design for the front of a portable grate, said front consisting of a three sided frame, a cast iron blower and the usual grate bars. - and fig. 2. is a horizontal section taken in the plane of the line A.B. fig. 1.

The three sided frame has near its exterior edge a swelled moulding - a a a a a &c., ornamented with alternate sunken ovals and circles, as shown at b-c. b-c. fig. 1. Across the top of the frame is a sunken panel, d. d. of the shape shown in fig. 1. the top being straight or horizontal, the two sides converging, and the bottom curved, - there being a series of ledges or steps all around said panel, as shown in the drawing.

On each side of said frame, and extending nearly the whole length, is a large sunken gothic panel, l l. l l.; having steps or ledges all around each, as shown in the drawing, and in the centre of each is a raised ornamental dash, (as printers would term it) - ff. shaped as as shown in fig. 1. On the exterior of each of the gothic panels, e. e. e. e. is a pilaster, g. g. having an ornamental capital, h. h. and base, i. i. and pinnacle, k. k. extending upwards from the top of each said capitals, h. h. On the inner side of said panels, is a triple column pilaster, l l. l l. having a capital m. m. and base, n. n. as shown in said fig. 1. and a flat arched swelled head, o. o. - spread from the top of one of said capitals, m. m. to that of the other.

Between the pilasters, l l. l l. on each side of the frame and the grate bars, k. k. k. k. &c. is a plain sunken gothic panel, g g. g g. the top of each having an arched rib around it, as shown in fig. 1.

The grate bars p p. p. p. are cast with the spaces between filled with metal. The blower made of cast iron, as before suggested, has all around it. a swelled moulding a. a. a. a. - ornamented, and in every perfect substantially similar -

to that before referred to at a a a a, as around the three sided frame.

On the front of said blower at proper intervals apart are four punk-
on gothic arches, 55-55. $\frac{1}{2}$. have steps or ledges around them, and in
the centre the ornamental dashes exactly in all respects like the
panels c.c.c. &c. The handle of the blower is also ornamented
with a series of leaves, arranged in the form of an ellipse, as
shown at t.t.

Having thus described my improved design, for
the front of a portable grate I shall state my claim as follows.

What I claim as my invention or production,
and desire to have secured to me by Letters Patent is the
combination of ornaments on the three sided frame, and blower
forming the front of a portable grate, consisting of the swelled
moulding, a a a a, with sunken ovals and circles, - the crop panel
and gothic panel, c.c.c., and pilaster, g g & C.C.-C.C. on the said
frame, and the similar gothic panel on the blower; all as
hereinbefore described, and represented in the accompanying
plate of drawings.
